COIN-OPERATED TABLE TENNIS GAME APPARATUS

Vernon L. Mott, Clinton, Mo.

Application November 29, 1950, Serial No. 198,105

6 Claims. (Cl. 194—9)

1

This invention relates to coin-operated game apparatus, and more particularly to an apparatus in which application of a coin actuates mechanism which effects movement of certain portions of the apparatus into position for the playing of the game, and after a predetermined time said portions are returned to position not suitable for playing of the game.

The objects of the invention are to provide a game apparatus with electrical circuits and devices which are energized responsive to insertion of a coin and actuate said mechanism to move an essential portion of the apparatus into game playing position and retain said portion in such position for a predetermined time and then release the essential portion for return to inoperative position where it is retained until another coin is inserted; to provide a coin-operated table tennis game apparatus with mechanism to raise a net relative to the table into playing position in response to insertion of a coin and lower the net to a non-playing or horizontal position on the table after a predetermined time interval; to provide an electrical circuit for a coin-operated table tennis game apparatus which provides positive control of the net and positioning of the net in playing position for a predetermined time interval; and to provide a coin-operated table tennis game apparatus which is economical to manufacture, easily assembled and maintained, and positive in operation to prevent unauthorized play of the game.

In accomplishing these and other objects of the present invention, I have provided improved details of structure, the preferred forms of which are illustrated in the accompanying drawings, wherein:

Fig. 1 is a perspective view of a table tennis apparatus with the net positioned in inoperative position.

Fig. 2 is a partial perspective view of the table tennis apparatus with the net in playing position, portions of the table being broken away to illustrate portions of the net operating mechanism.

Fig. 3 is a detail sectional view through the table illustrating the mounting of the net supporting shaft.

Fig. 4 is a bottom perspective view of the net operating device and position locks therefor.

Fig. 5 is a detail sectional view through the table on the line 5—5, Fig. 1, illustrating the position of the net actuating arm when the net is in lowered position.

Fig. 6 is a diagrammatic view of the electrical apparatus.

2

Referring more in detail to the drawings:

1 designates a coin-operated table tennis game apparatus which includes a table 2, having a top 3 provided with an upper surface 4 marked with the usual lines for designating playing areas. The table top is suitably supported on a base structure 5 which includes upwardly and inwardly sloping side and end panels 6 and 7 respectively, the upper ends of said panels being inwardly of the side and end edges of the table top to provide overhanging portions thereof which are boxed in by depending walls 8 secured to the under side of the table top at the side and end edges thereof and horizontal members 9 that extend from the lower edges of the walls 8 to the upper edges of the panels 6 and 7. The base 5 preferably also includes legs 10 in each corner thereof which extend from a supporting surface to the under side of the table top to provide a sturdy structure, the panels 6 and 7 preferably being removably secured to said legs. A net 11 of conventional structure extends transversely of the table top, substantially midway the length thereof, the ends of said net being removably secured by suitable fastening devices 12 to raising and lowering mechanism such as arms 13 fixed on the ends of a shaft 14 which extends through apertures 15 in the walls 8 and is rotatably mounted in bearing members 16 fixed to the table structure on the inside of the boxing formed by the members 8 and 9.

For facilitating assembly and economy of manufacture, it is preferable that the shaft 14 be made in two pieces, with the adjacent ends extending into a bore 17 of a sleeve 18 which has a depending arm 19 fixed thereto. The ends of the shaft are suitably secured in the bore 17 as by pins 21. The shaft 14 and the bearings supporting same are under the table top 3 and since it is desirable that the net 11 be vertical when in playing position and lie flat on the table top when not in use, the arms 13 are preferably L-shaped, as illustrated in Fig. 2, with the portion 22 thereof which connects the net-carrying portion 23 with the ends of the shaft 14 of a length substantially equal to the spacing between the shaft 14 and the upper surface 4 of the table top, and the shaft 14 so located that the net 11 is positioned by rotation of the shaft 14 in a vertical position, as illustrated in Fig. 2, when the table is in condition for playing table tennis, and lies flat on the table top, as illustrated in Fig. 1, when the table is not in playing condition.

The arm 19 extends through a slot 24 longitudinally of the table in a plate 25 secured to

the under side of laterally spaced longitudinal members 26, which are supported in spaced relation to the table top 3 by means of transverse members 21 suitably supported on the table structure. The lower end of the arm 19 extends through the slot 24 and is connected by a link 28 with the armature 29 of a solenoid 30 whereby pull on the armature and link rotates the shaft 14 and raises the net to playing position. A spring 31 has one end suitably connected to the lower end of the arm 19 and extends oppositely to the link 29, the other end of said spring being connected to the support members 26 to apply force to the arm 19, tending to rotate the shaft 14 to lower the net 11 flat on the table top 15 as illustrated in Figs. 1 and 5.

The movement of the net is controlled by an electric circuit 32. The electric circuit and devices thereof are all enclosed in the table structure so as not to be accessible to any unauthorized person. The circuit includes a transformer 33 having input terminals 34 and 35 connected by leads 36 and 37 respectively to a terminal plug 38 adapted to be connected with a suitable source of electric current, a suitable switch and fuse device 39 being connected in the leads 36 and 37 for controlling flow of current to the input side of the transformer. The output side of the transformer is provided with a plurality of terminals 40 arranged to have a plurality of low voltage parallel circuits connected thereto. A signal light 41 is connected in circuit with selected terminals 40 and adapted to be energized to indicate when the apparatus is in condition for operation or that current is being applied through the transformer 33. A conductor 42 is suitably connected to the output of the transformer 33 and to one end of a winding in a solenoid mechanism 43, the other end of said winding being connected through a timer or clock mechanism 44 to the transformer by a conductor 45. A switch 46 is interposed in the conductor 45, said switch being located in a coin chute 47 of a suitable coin mechanism, whereby the switch is in normally open position and is closed momentarily by passing of a coin through the coin chute. The coin mechanism is arranged adjacent one of the side panels 6, with the chute extending therethrough to present an open end 48 exteriorly of the panel 6 for receiving suitable coins.

The solenoid 43 has an armature suitably connected to an arm 49 of the timer 44 whereby energization momentarily of said solenoid moves the arm 49 to wind the clock mechanism, said arm and armature being gradually returned to starting position during the predetermined interval for which the timer mechanism is set to operate. The solenoid 43 and timer 44 are mounted on a suitable support, such as a plate 50, which also carries switches 51 and 52 which normally remain in circuit-breaking condition but are closed at the respective extremities of movement of the arm 49, the switch 51 being closed when the arm 49 is moved to wind the time mechanism and the switch 52 being closed when the arm 49 is moved to the extremity of its movement when the predetermined time interval for play has completely elapsed. One terminal of each of the switches 51 and 52 is connected by a conductor 53 to the output of the transformer 33. The other terminals of the switches are respectively connected by conductors 54 and 55 with one end of the winding of relay coils 56 and 57 respectively. Interposed in the conductor 54 is a switch

58 which is normally in closed position, said switch being suitably mounted on the plate 25 and having an arm 59 extending toward the path of movement of the arm 19 whereby when the arm 19 is moved to position the net in vertical condition a lug 60 on said arm will engage the arm 59 to open the switch 58, a spring 61 being arranged to return the switch 58 to closed position when the lug 60 is disengaged from the arm 59. A switch 62 also normally held in closed position by a spring 63 is interposed in the conductor 55, the switch 62 being suitably mounted on the plate 25 and having an arm 64 extending toward the path of movement of the arm 19 whereby when the spring 31 moves the arm 19 to lower the net onto the table top, the lug 60 will engage the arm 64 and open the switch 62. The other ends of the relay coils 56 and 57 are connected by a conductor 65 to the output side of the transformer. Connected to the conductors 54 and 65 in parallel with the relay 56 is a relay 66 which actuates a counter 67 each time the relay 56 is energized, which is each time the net 11 is raised to vertical position, thereby counting the number of times the apparatus is operated.

Energization of the relay coil 56 effects engagement of sets of contacts 68 and 69, and energization of the relay coil 57 effects engagement of a set of contacts 70 and disengagement of a set of contacts 71. One of each of the sets of contacts 68 and 70 is connected by a conductor 72 to the conductor 42. The other contacts of the sets 68 and 70 are respectively connected to branches 73 and 74 of a conductor 75 which is connected to one end of lock coils 76 and 77, the other ends of said coils being connected by a conductor 78 to the conductor 45 to complete the circuit to the output of the transformer, the coils 76 and 77 being in parallel circuit and suitably mounted on the plate 25 whereby armatures 79 and 80 operated by the respective coils 76 and 77 are movable across the path of movement of the arm 19, the armature 79 being adapted to engage the arm 19 on the side of said arm from which the spring 31 extends when the arm is in position for supporting the net 11 in vertical condition to retain same against lowering movement. The armature 80 is adapted to engage the arm 19 on the side thereof from which the link 28 extends when the arm is in position as shown in Fig. 5 with the net lowered on the table top whereby said armature 80 retains the arm 19 against net elevating movement. Each of the armatures 79 and 80 normally extends across the path of the arm 19 and energization of the coils 76 and 77 withdraws said armatures from the path of the arm 19 to permit movement of the same. A conductor 81 connects the input side of the transformer 33 with one of the contacts of the set 68, the other contact of the set being connected by a conductor 82 with one of the contacts of the set 71, the other contact of the set 71 being connected by a conductor 83 with one end of the coil of the solenoid 30, the other end of said coil being connected by a conductor 84 with the input side of the transformer to complete the circuit.

The game apparatus is normally in non-playing condition with the net 11 flat on the table top. If the electrical apparatus is not connected to a source of electric current the signal light 41 is not energized indicating the apparatus is not in condition for use. By connecting the plug 38 with a source of electrical current and oper-

ating the switch 39 to apply electrical current to the transformer 33 the signal light will be energized to indicate the apparatus is in condition for operation. Then by inserting a coin into the open end 48 of the coin chute 47 and releasing said coin, the coin will move downwardly through the chute, momentarily closing the switch 46 to complete a circuit from the output of the transformer through the conductor 42, solenoid coil 43, timer 44, conductor 45, switch 46, to the transformer energizing the solenoid and moving the arm 49 to wind the timer mechanism, the arm 49 being moved into position to close the contacts of the switch 41, completing a circuit for flow of current from the output of the transformer through the conductor 53, switch 51, conductor 54, switch 58, relay-coil 56 and relay coil 66, and conductor 65 to the transformer. The relay 66 actuates the counter 67 to advance same one number. The relay 56 closes the sets of contacts 68 and 69 for flow of current from the transformer through the conductor 42, conductor 72, set of contact points 68, branch 73, conductor 75, lock coils 76 and 77, and conductor 78 to the transformer, thereby energizing the coils 76 and 77 to retract the armatures 79 and 80 to permit movement of the arm 19. The relay 56 also completes a circuit from the input side of the transformer through the conductor 81, set of contacts 69, conductor 82, set of contact points 71, conductor 83, to the solenoid 30 and then through conductor 84 to the input side of the transformer; thereby energizing the solenoid 30 to retract the armature 29 to pull the arm 19 and rotate the shaft 14 to raise the net into vertical position. These circuits are maintained in closed condition for a short interval during which the arm 19 is moving to raise the net. When the arm 19 is in position with the net in vertical condition the lug 60 engages the arm 59 to open the switch 58 and the arm 64 being disengaged from the lug 60 allows the spring 63 to effect closing of the switch 62. Opening the switch 58 breaks the circuit to the relay 56, permitting the switch contacts 68 and 69 to return to normal open condition, thereby breaking the circuit to the lock coils 76 and 77 whereby the armatures 79 and 80 are moved across the path of the arm 19 whereby the armature 79 retains the arm 19 in position to maintain the net in vertical condition. The circuit to the solenoid 30 is also broken but the armatures of the lock coil move across the path of the arm 19 before the spring 31 can return the arm 19 to lower the net. The net 11 remains in playing position during a predetermined time interval determined by the timing mechanism 44.

At the end of the time interval the arm 49 moves into engagement with the switch 52 to close same, thereby completing a circuit from the output of the transformer through the conductor 53, switch 52, conductor 55, switch 62 to the relay 57, then through the conductor 65 to the output side of the transformer. This energizes the relay 57 which opens the set of contacts 71 whereby no current is delivered to the solenoid 30. The relay 57 also effects closing of the set of contacts 10, thereby completing a circuit from the transformer through the conductor 42, conductor 72, set of contacts 10, branch 74, conductor 75 to the lock coils 76 and 77 and then through the conductor 78 to the output side of the transformer, energizing the coils 76 and 77 to retract the solenoids 79 and 80, whereby the spring 31 draws the arm 19 to the other end

of its path of movement and lowers the net into horizontal position on the table top. Movement of the arm 19 disengages the lug 60 from the switch arm 59, thereby permitting the spring 61 to return the switch 58 to closed condition, and said lug 60 when the net is lowered will engage the switch arm 64 to open the switch 62. Opening of the switch 62 breaks the circuit to the relay 57, deenergizing the lock coils 76 and 77 whereby the armatures 79 and 80 are again moved across the path of the arm 19 and the armature 80 engages the arm 19 to retain same in position with the net horizontally on the table, which is a position not suitable for play of table tennis.

10 The net remains in locked, horizontal position and all circuits from the output side of the transformer are in interrupted condition except for the circuit to the signal light 41 which continues to burn, indicating the table is ready for further operation. The apparatus remains in this condition until another coin is inserted in the coin chute 47 for again actuating the apparatus to raise the net 11 to vertical condition.

15 It is believed obvious that I have provided an apparatus for a coin-operated tennis game which provides positive control of use of the apparatus for playing a game, the entire apparatus being economical to manufacture and easily maintained.

20 30 What I claim and desire to secure by Letters Patent is:

1. A game apparatus comprising, a rectangular table having a flat top and enclosed sides and ends, a net arranged transversely of the table top substantially midway the length thereof, net supporting means removably secured to the ends of the net and movably mounted in the table for raising and lowering the net to playing and non-playing positions respectively, a coin-receiving device, an operating arm operatively connected with the net supporting means within the enclosed portion of the table, a solenoid having an armature connected to the operating arm for moving same to raise the net to playing position, resilient means connected to the operating arm to return the net to non-playing position, a pair of electromagnets having movable armatures normally in the path of movement of the operating arm for retaining the net in selected position, switches in circuit with the solenoid and electromagnets respectively, relays for actuating said respective switches, other switches in series circuit with the respective relays and normally in circuit-making position, means on the operating arm engageable with the respective other switches at the limits of movement of the net for actuating said other switches to open the circuit to the respective relay, a timer mechanism, means responsive to insertion of a coin in the coin-receiving device for starting the timer mechanism and actuate the switches to complete circuits to effect raising of the net to playing position, and means actuated responsive to a predetermined operation of the timer mechanism for actuating the switches and completing circuits to effect lowering of the net to non-playing position.

2. A game apparatus comprising, a rectangular table having a flat top and enclosed sides and ends, a net arranged transversely of the table top substantially midway the length thereof, net supporting means removably secured to the ends of the net and movably mounted in the table for raising and lowering the net to playing and non-playing positions respectively, a coin-re-

ceiving device, a shaft rotatable in the table and having connection with the net supporting means for moving same, an operating arm fixed on the shaft within the enclosed portion of the table, a solenoid having an armature connected to the operating arm for moving same and operating the shaft to raise the net to playing position, resilient means connected to the operating arm for operating the shaft to return the net to non-playing position, a pair of electrically operated lock members normally in the path of movement of the operating arm for retaining the net in selected position, switches in circuit with the solenoid and electrically operated lock members respectively, relays for actuating said respective switches, other switches in series circuit with the respective relays and normally in circuit-making position, means on the operating arm engageable with the respective other switches at the limits of movement of the net for actuating said other switches to open the circuit to the respective relay, a timer mechanism, means responsive to insertion of a coin in the coin-receiving device for starting the timer mechanism, a switch actuated at the starting of the timer mechanism for completing circuits to the relays, electrically operated lock members and solenoids to release the operating arm and effect raising of the net to playing position by the solenoid, one of said other switches interrupting the circuits whereby the electrically operated lock members return to normal position and lock the net in playing position, and a second switch actuated by the timer after a predetermined interval for completing circuit to a relay and electrically operated lock members to release the operating arm for return of the net to non-playing position by the resilient means, the other of said switches interrupting the circuit to the relay and electrically operated lock members whereby the lock members thereof return to normal position to lock the net in lowered non-playing position and retain same until another coin is inserted into the coin-receiving device.

3. A game apparatus comprising, a rectangular table having a flat top and enclosed sides and ends, a shaft in and transversely of the table under the table top, arms fixed on the shaft for swinging movement, a net arranged transversely of the table top substantially midway the length thereof, means operatively connecting the net to the arms whereby swinging movement of the arms raise and lower the net to playing and non-playing positions respectively, a coin-receiving device, an operating arm fixed on the shaft within the enclosed portion of the table, a solenoid having an armature connected to the operating arm for moving same and rotating the shaft to raise the net to playing position, resilient means connected to the operating arm for rotating the shaft to return the net in non-playing position, a pair of electromagnets having movable lock members normally in the path of movement of the operating arm for retaining the net in selected position, switches in circuit with the solenoid and electromagnets respectively, relays for actuating said respective switches, other switches in series circuit with the respective relays and normally in circuit-making position, means on the operating arm engageable with the respective other switches at the limits of movement of the net for actuating said other switches to open the circuit to the respective relay, a timer mechanism, means responsive to insertion of a coin in the coin-receiving device for starting the timer mechanism, a switch actuated at the starting of the timer mechanism for completing circuits to the relays, electromagnets and solenoids to release the operating arm and effect raising of the net to vertical position by the solenoid, one of said other switches interrupting the circuits whereby the electromagnet armatures return to normal position and lock the net in vertical position, and a second switch actuated by the timer after a predetermined interval for completing circuit to a relay and electromagnet to release the operating arm for return of the net to lowered horizontal position by the resilient means, the other of said other switches interrupting the circuit to the relay and electromagnets whereby the armatures thereof return to normal position to lock the net in lowered horizontal position and retain same until another coin is inserted into the coin-receiving device.

5. A game apparatus comprising, a rectangular table having a flat top and enclosed sides and ends, a shaft in and transversely of the table under the table top and having portions extend-

ceiving device for starting the timer mechanism, a switch actuated at the starting of the timer mechanism for completing circuits to the relays, electromagnets and solenoids to release the operating arm and effect raising of the net to playing position by the solenoid, one of said other switches interrupting the circuits whereby the electromagnet lock members return to normal position and lock the net in playing position, and a second switch actuated by the timer after a predetermined interval for completing circuit to a relay and electromagnet to release the operating arm for return of the net to lowered non-playing position by the resilient means, the other of said other switches interrupting the circuits to the relay and electromagnets whereby the lock members thereof return to normal position to lock the net in lowered non-playing position and retain same until another coin is inserted into the coin-receiving device.

4. A game apparatus comprising, a rectangular table having a flat top and enclosed sides and ends, a shaft in and transversely of the table under the table top, arms fixed on the shaft for swinging movement from vertical to horizontal position, a net arranged transversely of the table top substantially midway the length thereof, means removably securing the ends of the net to the arms, a coin-receiving device, an operating arm fixed on the shaft within the enclosed portion of the table, a solenoid having an armature connected to the operating arm for moving same and rotating the shaft to raise the net to vertical position, resilient means connected to the operating arm for rotating the shaft to retain the net in horizontal position on the table top, a pair of electromagnets having movable armatures normally in the path of movement of the operating arm for retaining the net in selected position, switches in circuit with the solenoid and electromagnets respectively, relays for actuating said respective switches, other switches in series circuit with the respective relays and normally in circuit-making position, means on the operating arm engageable with the respective other switches at the limits of movement of the net for actuating said other switches to open the circuit to the respective relay, a timer mechanism, means responsive to insertion of a coin in the coin-receiving device for starting the timer mechanism, a switch actuated at the starting of the timer mechanism for completing circuits to the relays, electromagnets and solenoids to release the operating arm and effect raising of the net to vertical position by the solenoid, one of said other switches interrupting the circuits whereby the electromagnet armatures return to normal position and lock the net in vertical position, and a second switch actuated by the timer after a predetermined interval for completing circuit to a relay and electromagnet to release the operating arm for return of the net to lowered horizontal position by the resilient means, the other of said other switches interrupting the circuit to the relay and electromagnets whereby the armatures thereof return to normal position to lock the net in lowered horizontal position and retain same until another coin is inserted into the coin-receiving device.

ing outwardly from each side thereof, arms fixed on the outer ends of the shaft substantially parallel to the sides of the table for swinging movement from vertical to horizontal position, a net arranged transversely of the table top substantially midway the length thereof, means removably securing the ends of the net to the arms, a coin-receiving device, an operating arm fixed on the shaft within the enclosed portion of the table, a solenoid having an armature connected to the operating arm for moving same and rotating the shaft to raise the net to vertical position, resilient means connected to the operating arm for rotating the shaft to retain the net in horizontal position on the table top, a pair of electromagnets having movable armatures normally in the path of movement of the operating arm for retaining the net in selected position, switches in circuit with the solenoid and electromagnets respectively, relays for actuating said respective switches, other switches in series circuit with the respective relays and normally in circuit-making position, means on the operating arm engageable with the respective other switches at the limits of movement of the net for actuating said other switches to open the circuit to the respective relay, a timer mechanism, means responsive to insertion of a coin-receiving device for starting the timer mechanism, a switch actuated at the starting of the timer mechanism for completing circuits to the relays, electromagnets and solenoids to release the operating arm and effect raising of the net to vertical position by the solenoid, one of said other switches interrupting the circuits whereby the electromagnet armatures return to normal position and lock the net in vertical position, a second switch actuated by the timer after a predetermined interval for completing circuit to a relay and electromagnet to release the operating arm for return of the net to lowered horizontal position by the resilient means, the other of said switches interrupting the circuit to the relay and electromagnets whereby the armatures thereof return to normal position to lock the net in lowered horizontal position and retain same until another coin is inserted into the coin-receiving device,

and a counter actuated on starting of the timer for indicating the number of plays on the apparatus.

6. A game apparatus comprising, a rectangular table having a flat top and enclosed sides and ends, a net arranged transversely of the table top substantially midway the length thereof, net supporting means removably secured to the ends of the net and movably mounted in the table for raising and lowering the net to playing and non-playing positions respectively, a coin-receiving device, an operating arm operatively connected with the net supporting means within the enclosed portion of the table, an electric power means connected to the operating arm for moving same to raise the net to playing position, resilient means connected to the operating arm to return the net to non-playing position, electrically operated locking means having movable portions normally in the path of movement of the operating arm for retaining the net in selected position, switches in series circuit with the respective electrically operated locking means and normally in circuit-making position, means on the operating arm engageable with the respective switches at the limits of movement of the net for actuating said switches to open the circuit to the respective electrically operated locking means, a timer mechanism, means responsive to insertion of a coin in the coin-receiving device for starting the timer mechanism and energizing the electric power means to effect raising of the net to playing position, and means actuated responsive to a predetermined operation of the timer mechanism for actuating the switches and completing circuits to effect lowering of the net to non-playing position.
